UNITED STATES PATENT OFFICE.

FRANK X. ATZBERGER, OF RIDGEFIELD, NEW JERSEY.

INTERNAL-COMBUSTION ENGINE.

Application filed August 26, 1927. Serial No. 215,535.

The invention relates to internal combustion engines of the type which include a cooling system in which a circulation of water constitutes the cooling medium. Such systems, particularly when the engines are installed in automotive vehicles, are liable to become frozen when the temperature is at or below the freezing point, and in such cases oftentimes result in serious injury to the engine. 5 The object of the invention is to provide a novel and simple means whereby injury to the engine, as a result of freezing up of the cooling system will be efficiently and positively prevented. The invention will be fully described hereinafter and the features of novelty will be pointed out in the claims. 10

In the accompanying drawing, which illustrates an example of the invention without defining its limits, Fig. 1 is a diagrammatic elevation partly broken away of an engine equipped with the novel means; Fig. 2 is a diagrammatic plan view with parts in section; and Fig. 3 is a diagrammatic cross-section on the line 3—3 of Fig. 2.

25 The engine primarily may be of any usual type and conventional construction and includes the customary block 10 in which the cylinders 11 are located; in the illustrated example a head 12 is secured upon the block 10 by bolts 13 in the well known way. The block 10 and head 13 are provided respectively with chambers 14 and 15 which are in communication with each other and with the customary radiator or equivalent heat exchanging device and comprise part of the cooling system through which the water or other cooling fluid circulates.

As shown in Figs. 1 and 2 the chambers 14 and 15 are closed at their one ends and open 40 to the exterior of the engine at their other ends to receive tubes 16 and 17 respectively which preferably are closed at their inner ends and open at their outer ends; the tubes are made of brass, copper or other hard metal 45 having the inherent characteristic of returning to its original position and preferably are of elongated oval and flat form in cross section, as illustrated in Fig. 3. The tubes 16 and 17 furthermore are dimensioned to snugly 50 fit the openings at the ends of the chambers 14 and 15, and if desired, may be suitably packed to prevent leakage at these points. The aforesaid tubes extend throughout said chambers 14 and 15, as shown in Figs. 1 and 55 2 and are fixed in place therein in any convenient manner; in the preferred arrange-

ment the tubes are provided at their outer, open ends with outwardly projecting flanges 18 adapted to lie in surface engagement with the engine block 10 and head 12 respectively 60 for the accommodation of bolts or the like 19, whereby said tubes are removably secured in the chambers 14 and 15.

With this arrangement the tubes 16 and 17 are easily inserted into the respective chambers 14 and 15 until the flanges 18 engage the block 10 and head 12 respectively, said flanges, in addition to their other functions, serving thus to define the operative position of said tubes in the respective chambers. When in place the tubes 16 and 17 present surfaces of material area in the several chambers without however interfering with the circulation of the cooling water therethrough.

If at any time the water or its equivalent 75 in the chambers 14 and 15 should freeze, the pressure of the resulting ice upon the surfaces of the tubes 16 and 17 will compress the latter, so that any pressures thus developed will be absorbed by said tubes and consequently will have no effect to injure the engine. As the tubes 16 and 17 are thus compressed by the pressure of the frozen cooling medium, the air within said tubes will be forced therefrom through the outer open ends 80 of said tubes, so that no effective resistance to the aforesaid compression will be developed in the tubes. When, due to the thawing of the frozen water or its equivalent, the pressure on the tubes is relieved, the inherent 90 tendency of the metal to resume its normal position, will restore the tubes to their original cross-sectional form. The tubes in question thus provide an adequate and efficient 95 protection to the engine against injury from freezing up of the cooling system. By having the inner ends of the tubes 16 and 17 closed circulation of air therethrough whereby undesirable chilling or cooling of the engine might take place, particularly in the case 100 of a swiftly moving automotive vehicle, is avoided. Furthermore, the chambers 14 and 15 are easily provided with the openings through which the tubes 16 and 17 may be inserted, and the latter are easily placed in position in and removed from said chambers at 105 will. Repairs to the tubes or replacement thereof may thus be accomplished with a minimum of effort and in a minimum of time. The arrangement in addition is such that the 110 devices may be readily incorporated in existing engines at very small cost.

The improvement is of greater efficiency than an arrangement which includes closed tubes, for instance, as shown in my Patent #1,580,633, for the reason that the air in the closed tubes creates cushions therein which resist the compression of said tubes and thereby neutralize the beneficial effects thereof. Also in case the tubes develop leaks and permit the cooling medium or water to enter the same, such water or its equivalent may easily pass out of the open ends of said tubes, whereby freezing of any water which may leak into said tubes and interfere with the intended operation thereof is prevented. If it is found that the completely open ends of the tubes develop too great a cooling of the engine, due to the cool air in said tubes, provision may be made to reduce the area of said open ends without interfering with the exit of any water therefrom as described above; in such cases the air in said tubes would be trapped to a certain extent and consequently would become heated and thereby add to the efficiency of the engine, without however being prevented from passing out of said tubes should the latter become compressed because of the freezing up of the cooling fluid. Furthermore, the closed tubes located in the closed chambers, as in said patent, present structural problems which are difficult and expensive to overcome.

Various changes in the specific form shown and described may be made within the scope of the claims without departing from the spirit of the invention.

35 I claim:

1. The combination of an internal combustion engine provided with cooling chambers comprising part of a circulating water cooling system, said chambers having openings to

the outer air, and tubes of hard metal having an elongated form in cross-section fitted in said openings and extending into said chambers, said tubes having their inner ends closed and provided with openings communicating with the outer air at their outer ends.

2. The combination of an internal combustion engine provided with cooling chambers comprising part of a circulating water cooling system, said chambers having openings to the outer air, tubes of hard metal having elongated flat form in cross-section fitted in said openings and extending into said chambers, said tubes having their inner ends closed and their outer ends open, flanges at the outer ends of said tubes adapted to lie against said engine, and fastening means extending through said flanges into said engine for securing said tubes in place.

3. In an internal combustion engine, the combination of a cylinder block, a head carried by said block, said block and head being provided with cooling chambers comprising parts of a circulating water cooling system and having openings to the outer air, hard metal tubes of elongated, flat cross-section fitted into said openings and extending into said chambers, said tubes having their inner ends closed and their outer ends open, outwardly projecting flanges at the open ends of said tubes adapted to lie against the surfaces of said block and head to determine the operative position of said tubes in said chambers, and bolts extending through said flanges into said block and head respectively for fixing said tubes in place.

In testimony whereof I have hereunto set my hand.

FRANK X. ATZBERGER.
